UNITED STATES PATENT OFFICE.

MORRIS J. MURPHY, OF CHICAGO, ILLINOIS.

DESIGN FOR A BASE FOR LAMPS, ETC.

Application filed February 27, 1925. Serial No. 12,500. Term of patent 3½ years.

To all whom it may concern:

Be it known that I, MORRIS J. MURPHY, a citizen of the United States, residing at Chicago, in the county of Cook and State of Illinois, have invented a new, original, and ornamental Design for a Base for Lamps, Etc., of which the following is a specification, reference being had to the accompanying drawing, forming part thereof, wherein is exhibited in perspective a base embodying my new design.

I claim:

The ornamental design for a base for lamps, etc., as shown.

MORRIS J. MURPHY.
